UNITED STATES PATENT OFFICE.

HARRY W. BRADNER, OF TACOMA, WASHINGTON, ASSIGNOR, BY DIRECT AND MESNE ASSIGNMENTS, TO THE GENERAL PATENTS COMPANY, INC., OF NEW YORK, N. Y., A CORPORATION OF NEW YORK.

EXTENSION-TABLE.

1,079,927.

Specification of Letters Patent. Patented Nov. 25, 1913.

Original application filed May 20, 1912, Serial No. 698,447. Divided and this application filed February 8, 1913. Serial No. 747,026.

To all whom it may concern:

Be it known that I, HARRY W. BRADNER, a citizen of the United States, residing at Tacoma, in the county of Pierce and State 5 of Washington, have invented a certain new and useful Improvement in Extension-Tables, of which the following is a specification.

The invention relates to extension tables 10 in the class of household furniture and more particularly to that type supported at the center by a pedestal or legs, and the objects of the invention are to provide mechanism by which the halves of the table-top are so 15 connected as to move oppositely to equal distances in the opening and closing movements, thus maintaining balance, and permitting the table to be opened or closed by one person alone at one end, the other end 20 moving automatically, and to provide means for insuring the easy movement of the slides and lessening or entirely avoiding the liability of the moving parts to bind.

The invention consists in certain novel 25 features and details of construction by which the above objects are attained, to be hereinafter described.

The accompanying drawings form a part 30 of this specification and show an approved form of the invention.

Figure 1 is a plan view of the table in the opened condition. Fig. 2 is a plan view of the slides and connected parts on a larger scale, the table-top being indicated by dotted lines. Fig. 3 is a corresponding vertical section taken transversely of the slides on the dividing line of the table-top and partly in elevation. Fig. 4 is a central vertical section of a portion, taken at a right angle to 35 the view in Fig. 3, and partly in elevation. The remaining figures are on a still larger scale and show the construction of the slides. Fig. 5 is a transverse vertical section through 40 the slides. Fig. 6 is a corresponding horizontal section, partly in plan view, the plane of section being indicated by the line 6-6 in Fig. 5. Fig. 7 is an elevation of the working face of one of the slides.

Similar letters of reference indicate the 50 same parts in all the figures.

A is the upper part of a pedestal having a cap-piece A¹ carrying the operating mech-

anism and supporting the two halves A² A² of the table-top. Mounted upon and fixed to the cap-piece near each end is a fixed 55 guide C forming the central member of a set of slides to be further described, and at the center, lying parallel with the slides, is fixed a bar D extending diametrically of the table and as nearly as may be to the outer 60 margin of each half of the table-top when in the closed condition. It carries on its upper face at each end a horizontal pulley E partially encircled by a cord or belt F which is in effect continuous but is divided 65 at two points for attachment to the ends of arms G G located between the center-bar D and the sets of slides, each fixed to one portion of the table-top and extending some distance beyond the dividing line between 70 the two halves thereof. By this arrangement of cords and pulleys a movement of one portion of the table top is communicated to the other, so that in opening or closing the table-top the movement of one half in 75 either direction automatically causes a corresponding movement of the other half to the same extent and in the opposite direction, thus insuring the desired balance and permitting the opening and closing movements to be easily effected by one person pulling or thrusting on one of the halves alone. In order to utilize effectually the support offered to each half by the overhanging ends of the strong central bar D, 80 the vertical pins E¹ E¹ which serve as centers or pivots for the pulleys E E are each provided with a forked head or yoke E² in which is mounted a small grooved roller H matching a cylindrical track H¹ on the 85 under face of each portion of the table-top, and which may be a cylindrical wire lying upon or partially embedded in such face and secured by driving its upturned ends H² H² into the material of the table. The 90 tracks and rollers permit the table-top to be supported by the central bar D at points as distant as practicable from the center of the table, and allow the halves to be moved anti-frictionally relatively to such bar. The 95 sets of slides are also constructed to move with a minimum of friction while maintaining reliable engagement each with its neighbor. Each set is the counterpart of the other 100

and comprises the relatively fixed central member C above referred to, and a slidable member J or K on each of the side faces thereof, one attached to one portion of the 5 table-top and the other to the opposite portion, to move therewith.

The adjacent faces of the several slides J, C, K, are grooved near the upper and lower edges to produce channels as at *j c k* and form the longitudinally extending central ribs J¹ C¹ C² K¹ between the channels. On each rib is a strip or flat bar of metal B wider than the rib and extending partially over the adjacent channels, and having its 10 edges rounded. These strips B B lie face to face in pairs and at one end each is forked as at B¹ and the branches folded to form housings B² receiving pins B³ serving as shafts for small rollers B⁴ mounted in the 15 housings and grooved on the periphery to match closely and engage the rounded edges of the adjacent strip. The fork B¹ of each strip is at the opposite end from its neighbor, and the overhanging portions of the 20 housings and their rollers are received in the channels. The strips of each pair are thus joined with liberty to move longitudinally relatively to each other with their attached 25 slides, the rollers serving as the means of engagement and in reducing the friction. To limit the outward movement of the strips and slides and the separation of the two halves of the table-top, a projection or spur B⁵ is produced on the upper edge of each 30 strip at the proper location, arranged to strike or be struck by the upper roller B⁴ of the adjacent strip and arrest the outward movement; the inward movement is arrested 35 by the contact of the two halves of the 40 table-top, as will be understood.

Thus constructed and arranged, the several parts of the table are reliably joined while the required movements are permitted with but little friction, and slight changes 45 of the materials employed, due to hygrometric conditions, do not interfere with the working of the mechanism.

Modifications may be made in the forms and proportions of the parts without departing from the invention, and parts may 50 be used without the whole.

The cord F may be a chain or other flexible connection, and the track H¹ may be con-

structed and attached in a different manner than that shown and described. 55

No claim is made in this application to the cord-and-pulley mechanism for separating and closing the table-top, such being made the subject-matter of an application filed May 20, 1912, Serial No. 698,447. 60

I claim:

1. In an extension table of the character set forth, two relatively movable slides, each having channels on the face presented to the adjacent slide, a rib between such channels, 65 a strip of metal extending longitudinally of each rib and secured thereto, a fork at one end of each of said strips and oppositely located relatively to the adjacent strip, housings in the branches of said forks, and rollers mounted in said housings and engaged 70 with the upper and lower edges of the adjacent strip.

2. In an extension table, two relatively movable slides, each having a strip of metal 75 extending longitudinally and secured thereto, a fork at one end of each of said strips and oppositely located relatively to the adjacent strip, housings in the branches of said forks, rollers mounted in said housings 80 and engaged with the upper and lower edges of the adjacent strip, and stops for limiting the outward movement of said slides, consisting of spurs on the edge of said strips, formed integrally with the latter in the 85 paths of said rollers.

3. In an extension table two relatively movable slides each having a flat strip of metal extending longitudinally thereof and secured thereto, each strip being slotted at 90 one end thereof to separate the strip into two branches, said branches diverging in the planes of their respective strips and the terminal of each of said branches being bent over to form a hook-shaped flange extending 95 over the adjacent edge of the opposite strip into engagement with the rear surface of the latter.

In testimony that I claim the invention above set forth I affix my signature, in presence of two witnesses. 100

HARRY W. BRADNER.
